DESIGN FOR A TUMBLING MACHINE

George E. Huenerfauth, Park Ridge, Ill., assignor
to Crown Rheostat & Supply Co., Chicago, Ill.,
a corporation of Illinois

Application March 31, 1944, Serial No. 113,098

Term of patent 14 years

(Cl. D55—1)

To all whom it may concern:

Be it known that I, George E. Huenerfauth, a citizen of the United States, residing at Park Ridge, in the county of Cook and State of Illinois, have invented a new, original, and ornamental Design for a Tumbling Machine, of which the following is a specification, reference being had to the accompanying drawings, forming part thereof, in which—

Fig. 1 is a front elevational view of a tumbling machine showing my new design;

Fig. 2 is a plan view of the tumbling machine;
Fig. 3 is a rear elevational view of the tumbling machine; and

Fig. 4 is an end view of the tumbling machine.

I claim:

The ornamental design for a tumbling machine, substantially as shown.

GEORGE E. HUENERFAUTH.
